[57] **CLAIM**

The ornamental design for a fishing rod holder, as shown and described.

DESCRIPTION

FIG. 1 is a perspective view of a fishing rod holder showing my new design, the broken-line showing of the fishing rod and of the second holder in a closed position being for illustrative purposes only and forming no part of the claimed design;

FIG. 2 is a front elevational view thereof;

FIG. 3 is a right side elevational view thereof;

FIG. 4 is a left side elevational view thereof;

FIG. 5 is a rear elevational view thereof; and

FIG. 6 is a top plan view thereof, the bottom being substantially a mirror image of that shown. The strap elements in FIGS. 2-5 are shown broken-away for ease of illustration.
